UNITED STATES PATENT OFFICE

JOSEPH H. LANGROCK, OF NEW HAVEN, CONNECTICUT

NONSLIP DEVICE FOR GARMENTS

Application filed March 5, 1930. Serial No. 433,230.

This invention relates to a device intended for attachment to a garment, and particularly to the inner face of the waist-band of men's trousers for the purpose of preventing the same from slipping down while being worn. Through the use of such a device as forms the subject of my invention, the necessity for wearing a tight-fitting and consequently an uncomfortable trouser-supporting belt or 10 suspenders is avoided.

The object of my invention therefore, is to provide a device of the character mentioned, which when worn, is wholly invisible; which in no manner causes inconvenience to the 15 wearer, and which acts to effectively prevent the garment to which it attached from slipping down, either completely dispensing with the use of a belt or suspenders, or else permitting the use of a very loosely worn 20 comfortable belt, should the wearer prefer to wear any at all.

While I have herein set forth the fact that the non-slip device forming the subject matter of this invention, is particularly adapted 25 for use on the waist-bands of trousers, it will be apparent that there are many other uses to which it may be put, as for example on the inner face of men's vests or waistcoats, to prevent the same from rising or sliding up on the 30 wearer's body. Many other meritorious uses for my device will be apparent to those skilled in the art to which it relates.

With the objects above set forth, and such other objects as may hereinafter appear, in 35 view, I have devised the particular embodiment described below and more particularly pointed out in the claims appended hereto.

Reference is to be had to the accompanying drawings, forming a part hereof, in 40 which

Figure 1 is a plan view of my improved non-slip device attached to the inner face of a garment waist-band;

Figure 2 is a sectional view on the line 2—2 45 of Figure 1, looking in the direction of the arrows; and

Figure 3 is an end view of the device, with a portion of the cup-shaped member broken away to disclose construction.

Throughout the various views of the draw-

ings, similar reference characters designate similar parts.

In the embodiment of my invention as disclosed in the accompanying drawings, 1 indicates the outer cover member of the device, 55 the same consisting of a concavo-convex or cup-shaped shell or disk made of a soft, yielding and elastic material, such as soft rubber. The member 1 is made in any suitable way, such as in a suitable mould. It is so moulded 60 as to provide its outer or convex surface with a plurality of ribs, as at 2, whereby an outer roughened or serrated gripping surface is afforded.

As clearly shown in Figure 1 of the drawings, the ribs 2, formed as above described, are so arranged that when the device is attached to a garment, said ribs extend across or transversely of the longitudinal axis of the body of the wearer. Thus, if the device, 65 or several of these devices, are attached for instance, to the inner face of the waistband of trousers, any downward slipping tendency 70 of the trousers would occur across the axis of the ribs, the ribs consequently setting up a 75 maximum of resistance to any such slipping tendency.

To aid in moulding the cup-shaped shell 1, I arrange the ribs 2 so that the same terminate short of the ends of the shell, thus producing the unribbed terminations 3.

The shell 1 is provided at its base with a peripheral, laterally extending, flange 4, which is pierced at intervals with holes 5 through which stitches 6 may be passed to 85 secure the shell to the inner face or lining 7 of a trouser waist band 8, or to any other desired portion of a garment where the use of a device of the character described is necessary or desirable.

At 9 is shown a soft, yielding, and highly elastic, cushioning member or backing, which is so shaped as to fit within and be wholly enclosed by the concave side of the cup-shaped shell 1 wherein it may, if desired, be 95 adhesively or otherwise secured, or else it may merely be frictionally held in position. This cushioning member 9 is preferably made of sponge rubber, or of material having similar characteristics. It has a rounded outer 100

face 10 conforming generally in shape to the inner or concave side 12 of the member 1, but being of less thickness than the depth of the member 1 so that an air-space 11 is provided 5 between the outer face 10 of the cushion 9 and the inner face 12 of the member 1. Thus, when pressure of the user's body is exerted against the outer rubber surface 2 of the rubber shell 1, this shell may slightly collapse or 10 flatten under such pressure, the air space 11 permitting such flattening action and allowing the member 1 to shape itself to the surface against which it presses. The sponge rubber cushion 9 acts to firmly, yet resiliently, and without causing the slightest trace of 15 discomfort, hold the device against the body of the wearer, and acts effectively to prevent the slipping or shifting of any garment to which it may be attached.

20 In use, a number of these devices may be attached at spaced intervals to the waist band of a garment and the same will serve to effectively support the garment without requiring the use of a tightly adjusted belt 25 or the use of uncomfortable suspenders. Incidentally, when these devices are used upon trousers, they serve in a dual capacity. That is, while preventing the descent of the trousers, they also exert pressure against the 30 wearer's shirt which is tucked in the trousers, and prevent the shirt from rising.

While I have herein described my improved nonslipping device as being especially adaptable for use on men's trousers, it will 35 be apparent that it may readily be used on many other garments, such as was heretofore specified, as for instance, on the inner side of men's waistcoats, acting to prevent the same from sliding upward. It also may be 40 used on women's garments in any capacity wherein its non-slipping functions may operate to advantage.

This device is so constructed that it can 45 be attached to garments while they are being made, or it can be sold separately to be attached to a garment separately or previously purchased, since it may be easily attached to any garment by anyone with a minimum of skill and effort.

50 Having described one embodiment of my invention, it is obvious that the same is not to be restricted thereto, but is broad enough to cover all structures coming within the scope of the annexed claims.

55 What I claim is:—

1. A device of the class described comprising a circular cup-shaped collapsible shell having an externally roughened surface and means adjacent to the peripheral edge for 60 attaching it to a garment.

2. A device of the class described comprising a yielding cup-shaped exteriorly roughened shell, a yielding cushioning means disposed behind and wholly contained within 65 said shell, and means for attaching said shell

to a garment comprising a laterally extending portion on said shell at its base.

3. A device of the class described comprising a yielding cup-shaped exteriorly roughened shell, a yielding cushioning means disposed behind said shell, and means for attaching said shell to a garment comprising a peripheral flange located at the base of the shell. 70

4. A non-slip device for garments comprising a cup-shaped outer member of ribbed rubber, and a soft sponge rubber pad contained within and disposed behind the same and means at the periphery of the shell for attaching it to a garment. 75

5. A device of the class described comprising a hollow, exteriorly roughened yielding outer member, a yielding pad disposed behind and wholly enclosed by said outer member, said pad being of less thickness than the depth of the outer member whereby a space is provided between the face of said pad and the inner face of said outer member. 80

6. A non-slip device for garments comprising a hollow shell having its outer face provided with a plurality of ribs, a soft rubber pad disposed within and providing a backing for said shell, said pad being of less thickness than the depth of the shell whereby a space is provided between the face of said pad and the inner face of said shell, said space permitting a flattening action of the shell before it exerts pressure on said pad. 85

Signed at the city of New York, county of New York, and State of New York, this 4th day of March, 1930.

JOSEPH H. LANGROCK.
